UNITED STATES PATENT OFFICE.

MINOT H. BATES, OF BROCKTON, MASSACHUSETTS.

DESIGN FOR A SHOE OR ANALOGOUS ARTICLE.

Application filed May 7, 1926. Serial No. 17,596. Term of patent 3½ years.

To all whom it may concern:

Be it known that I, MINOT H. BATES, a citizen of the United States, residing at Brockton, in the county of Plymouth and Commonwealth of Massachusetts, have invented a new, original, and ornamental Design for a Shoe or Analogous Article, of which the following is a specification, reference being had to the accompanying drawing, forming a part thereof.

In the accompanying drawing there is

shown the representation of a conventional shoe in perspective, embodying my new design, the dominant feature of which is the welt strip, piping and binding each having a surface provided with a pair of thin lines alternating with a thick line.

I claim:

The ornamental design for a shoe or analogous article, substantially as shown and described.

MINOT H. BATES.
